UNITED STATES PATENT OFFICE

OTTO W. SCHAUM, OF PHILADELPHIA, PENNSYLVANIA, ASSIGNOR TO FLETCHER WORKS, INCORPORATED, OF PHILADELPHIA, PENNSYLVANIA, A CORPORATION OF PENNSYLVANIA

WHORL LATCH

Application filed December 27, 1930. Serial No. 505,092.

My invention relates to improvements in whorl latches for spinning and twisting machines, and has for one of its objects the provision of a whorl latch which is of simple 5 construction, neat appearance and which nevertheless will withstand the rough usage to which it is subjected.

With my improved construction the whorl latch may be made by automatic machinery, 10 the latch support being applied to the base or step after the same has been made, thereby resulting in considerable saving in the cost of manufacture.

Another object of my invention is the provision of a latch construction which can be 15 readily operated by the thumb and finger of the operator or with one finger of either hand as compared with latches of previous constructions wherein a tool is required to operate the latch. My improved latch is also 20 so constructed and arranged that the same can be operated by inserting the spout of an oil-can under the lower portion thereof, this being an advantage inasmuch as the operator when oiling the machine is required to 25 hold an oil-can in one hand and raise the blade and whorl with the other leaving no hand free to operate the latch.

A further object of my invention is the 30 provision of a latch which may be raised out of operative position so that the same will rest against the whorl and remain in that position, the removal of the whorl causing the latch to return to operating position.

In the drawing wherein I have illustrated 35 one embodiment of my invention:

Fig. 1 is a sectional elevation of my improved whorl latch.

Fig. 2 is a sectional view on line 2-2 of 40 Fig. 1 looking in the direction of the arrows; and

Fig. 3 is a perspective view showing the latch in detail.

Referring to the drawing in detail: 1 designates a spindle blade rotatable vertically in a roller bearing bolster 2. This bolster rests upon a base 3 the lower portion of which is screw-threaded at 4 whereby the same is secured to the machine. The base 3 is provided with a shoulder 5 against which a latch 45

support 6 is pressed, this latch support being of pressed steel and provided with a hole of the proper diameter to make a press fit on the housing. The upwardly extending portion 6' of the latch support 6 is provided with a 55 turned over portion 7 to support a stud 8 which carries a latch 9 pivoted intermediate its ends on the stud 8.

A whorl 10 is frictionally held on the spindle 1 and has its lower end provided with a flange 11. The latch 9 is provided with whorl engaging portions 12 which when the latch is in operating position are in the path of the flange 11 of the whorl. The other end 13 of the latch extends downwardly when 65 the latch is in operative position, the lower end extending out of the plane of the adjacent portion of the support whereby an actuating lip or projection 14 is provided so that the spout of an oil-can or the finger of the operator 70 may readily be inserted beneath this lip to rotate the latch about its pivot 8 out of operative position.

It will be noted that the latch may be moved out of operative position by pivoting 75 the portion 13 to bring the center of gravity of the latch between the pivot 8 and the whorl so that the latch will remain in the detted line position of Fig. 1. When the latch is in this inoperative position it will 80 be obvious that the whorl may be removed, the flange 11 on the whorl during this operation engaging the tail 13 of the latch so that the same will fall about its pivot into 85 operative or normal position. Of course in placing the whorl again in position the flange 11 will engage the latch to move the same downwardly sufficiently to permit the flange to pass.

While I have illustrated and described a 90 preferred form of my invention it is to be understood that I do not wish to be limited to this precise arrangement and construction inasmuch as various modifications may be made without departing from the spirit and 95 scope of my invention.

What I claim is:—

1. In combination, a whorl, a latch therefor, a support for the latch, said latch being pivoted intermediate its ends on said sup- 100

port whereby the latch may be rotated to bring its center of gravity between its pivot and the whorl, said pivot being so located that the latch will be held by gravity in both latching and unlatched positions.

2. In combination, a flanged whorl, a spindle blade, a latch support, a latch for said whorl pivoted intermediate its ends to said support and provided with a weighted

10 portion and a whorl-engaging portion, said whorl engaging portion being normally in the path of said flange, said latch being rotatable on said support to a position where the weighted portion will rest against the 15 whorl and be sustained in that position until engaged by the flange of the whorl upon removal of the whorl, such movement of the whorl moving the latch to such position that it will be carried by gravity to its normal 20 operative position.

3. In combination, a flanged whorl, a latch support, a whorl latch pivotally mounted on said support, a portion of said latch when the latch is in operative position projecting out

25 of the plane of the adjacent portion of said support to facilitate the pivoting of said latch out of operative position to a position where the projecting portion of the latch will engage the whorl, removal of the whorl 30 with the latch in said inoperative position pivoting the latch in the opposite direction to a position where it will be restored by gravity to its original operative position.

4. A whorl latch, and a support therefor 35 to which said latch is pivoted, the pivot of said latch being so disposed relatively to the center of gravity of the latch that gravity tends to maintain the latch in latching position, and to maintain the latch in unlatched 40 position upon rotation of the latch through an arc less than 360°.

5. A whorl latch, a support therefor to which the latch is pivoted the center of rotation of the latch being an appreciable distance from its center of gravity, said latch having a body portion and a whorl engaging portion the latter holding the whorl latched against removal when the body portion of the 45 latch engages the said support, removal of the whorl being permitted when the latch is rotated until its said body portion engages the whorl.

6. In combination, a whorl, a whorl latch, a spindle blade, said latch being rotatable 55 through an arc less than 360° about a horizontal axis out of the plane of the spindle blade, said latch having at least two positions of rest, one position permitting removal of the whorl, another preventing such removal.

This specification signed this 24th day of December, 1930.

OTTO W. SCHAUM.
